M. T. Lincoln.
Galley Rest.

No. 96,929. Patented Nov. 16, 1869.

Inventor,

M. T. Lincoln.

United States Patent Office.

M. T. LINCOLN, OF WASHINGTON, DISTRICT OF COLUMBIA, ASSIGNOR TO
HIMSELF AND WILLIAM ROBINSON, OF SAME PLACE.

Letters Patent No. 96,929, dated November 16, 1869.

IMPROVEMENT IN GALLEY-RESTS.

The Schedule referred to in these Letters Patent and making part of the same.

To all whom it may concern:

Be it known that I, M. T. LINCOLN, of Washington, in the county of Washington, and District of Columbia, have invented certain new and useful Improvements in Type-Case Stands, by Attaching a Combined Galley-Rest and Galley thereto; and the following is a full, clear, and exact description of the same, reference being had to the accompanying drawings, making a part of this specification, in which—

Figure 1 represents a sectional view.

Figure 2 is a front elevation.

Figure 3 is a top view of the sliding board.

Figure 4 is a bottom view of the same.

Figure 5 is a top and end view of the galley-head.

Figure 6 is a view of the socket for galley-head.

Figure 7 is a perspective view of the type-stand, showing the sliding board drawn out for use.

Figure 8 is a sectional view of the type-stand, with the sliding board or galley-rest closed.

The object of my invention is to provide an ordinary type-case stand with an adjustable galley-rest, which may also be used for the purpose of a galley or slide-galley.

My invention consists in the employment of a device for the triple purpose of a galley-rest, type-galley, and slide-galley, for printers' use.

To enable others to make and use my improved galley-rest and galley, I will proceed to describe its construction and operation, referring by letter to the accompanying drawings.

To the frame of an ordinary type-case stand, A, figs. 1 and 7, I fasten strips *a a* of wood, so as to give an incline of about ten degrees, upon which I place a board or table, B, figs. 1, 2, 7, and 8, also shown detached from the frame in figs. 3 and 4, fitted so as to slide easily.

At the rear end, and on the under side of this board, a piece of wood, *b*, (figs. 1, 7, and 8, also, detached views, figs. 3 and 4,) is fastened transversely, the ends of which are rabbeted, so as to fit the strips *a a* and form lips, which, passing under them, prevent the board from tipping up when drawn out, and also make a guide for the rear end.

The front part of the frame A is cut away sufficiently to allow the board B to be fitted in, so as to come a little below the top, and not interfere with the type-case.

Fastened on the under side of the board B, is a ratch, *c*, shown in figs. 1, 4, and 8, into which works a pawl, *d*, figs. 1 and 8. This pawl is attached to the frame A, and is so constructed that gravitation keeps it in contact with the ratch.

There are also placed, on the under side of the sliding board, stops *e e*, fig. 4, which prevent it from being drawn out too far.

On the top and right-hand side of the board is a metallic plate, C, fig. 3, and enlarged view, fig. 5.

This plate is connected to the board or table, by means of dovetail projections *f f*, (fig. 5, end view,) on its under side, which fit into corresponding sockets *g g*, in another metallic plate D, fig. 6, which is let in flush with the surface of the board, and firmly fastened thereto, by which means it can be attached or detached at pleasure.

On the upper front edge of the table B, a piece, *h*, figs. 1 and 2, is fixed, at a right angle with its surface, sufficiently high to prevent the galley from sliding off when placed upon it, and also to form the side angle of the galley when used as such.

The upper left edge of the board is slightly rabbed, so as to form a ledge, *i*, figs. 2 and 3, upon which an ordinary galley may rest in sliding type from my device on to said galley, and *vice versa*.

The materials used in the construction of my device or attachment, may be wood, or any other material that may be found to be best suited for the purpose.

The operation, use, and advantages of my improvement, I will now proceed to set forth.

The sliding board or galley-rest B is, when closed, kept in place by the pawl *d* operating into the ratch *c*, as shown in fig. 8.

When the rest is desired for use, the pawl being released from the ratch, it can be drawn out to any required distance; then, by allowing the pawl to fall back into the ratch, it is secured in position, as shown in fig. 1. To slide it back into the frame, it is only necessary to press upon it with the hand, as the ratch does not interfere to prevent its going back.

The stops *e e*, fig. 4, coming in contact with the frame on the inside, prevent its being drawn out beyond a certain distance.

When the rest is desired for use as a galley, the galley-head C is attached, by being placed in position, and fastened by means of the dovetailed projections, which, fitting into the corresponding sockets in plate D, secure it in place. This plate C being at a right angle to the board, forms, with the front piece *h*, a galley.

The galley-head C can be removed at pleasure, as, when the ordinary galley is in use, it is not needed, and might prove an obstruction.

By using this attachment, a place is provided for resting the galley, thereby leaving the cases entirely unencumbered.

It is well known that with the present arrangement the galley is laid upon the type-case, and must necessarily be moved to get at the type, which often injures both case and type.

By this improvement, the compositor can work

with his galley always in front of him, and his case free at his right.

It facilitates and expedites the correction in page-form as well as on galleys.

When in use, the attachment is no obstruction to the compositor.

It is so firmly connected to the frame, there is no danger of the accidental detachment of the mechanism.

It occupies only that space heretofore unavailable in the frame, and adds to its strength when not in use. By a slight movement of the hand, it can be placed entirely out of the way.

Having thus fully described my invention,

What I claim as new, and desire to secure by Letters Patent, is—

1. The movable board B, ratch c, and pawl d, in combination, all constructed and arranged substantially as and for the purposes specified.

2. The detachable galley-head C, in combination with the rest B, constructed substantially as and for the purposes described.

In testimony whereof, I hereunto subscribe my name.
